CLAIM

The ornamental design for a combined umbrella and body attachable umbrella support, as shown and described.

DESCRIPTION

FIG. 1 is a perspective view of a combined umbrella and body attachable umbrella support showing my new design therefor. The broken line drawing representing a human figure is for purposes of illustration only and forms no part of my design.

FIG. 2 is a front elevational view;

FIG. 3 is a rear elevational view;

FIG. 4 is a top plan view;

FIG. 5 is a left side elevational view;

FIG. 6 is a right side elevational view; and,

FIG. 7 is a bottom plan view.

FIG. 1**FIG. 2****FIG. 3****FIG. 4****FIG. 5****FIG. 6****FIG. 7**
